UNITED STATES PATENT OFFICE.

OSCAR A. PEDERSEN, OF NEW YORK, N. Y.

BUILDING CONSTRUCTION.

Application filed June 15, 1927. Serial No. 198,944.

This invention appertains to improvements in building constructions and more particularly in buildings in which the walls are formed and built up of large units or slabs of concrete or other cementitious material.

The invention aims to provide a novel and effective means and method of connecting and securing the slabs or units of the building together and finds particular application in the 10 uniting and joining of the various walls of the building.

The necessity for an efficient means for uniting, joining, and connecting the walls of a building constructed of a self-setting cementitious material such as concrete or mortar has long been recognized. Such material is non-elastic and does not yield or give in response to changes due to warping or movement in the 15 columns or framework of the building.

Most connecting means hitherto used have been ineffective because they allow some play between the walls or units connected and generally fail to secure and connect them together rigidly so as to prevent any movement there- 20 between. The result of the play and loose connection between the units or walls is to cause cracking in the material of the walls or units with consequent deterioration in the 25 walls and the imposition of an unsightly appearance upon the walls.

By my invention I provide a simple, novel and effective connecting means for uniting and joining slabs, building units and walls. This connecting means is substantially rigid 30 so as to eliminate play or relative movement between the elements united and connected and is also of such a character and nature as to permit ready and convenient attachment to the elements to be connected and to allow the 35 various units or elements to be united, connected, and assembled easily and efficiently, and disassembled if necessary. The connecting means is preferably such as to pull and draw the building units together during application and to maintain them when applied in tight and firm cooperation whereby no relative movement between the units may occur.

In the drawings:

Figure 1 is a sectional plan view through an outer corner of a building in which the walls are connected by my improved means.

Figure 2 is a sectional plan view through a corner formed at the meeting of an interior partition wall and an outside wall and showing the application of the invention to the connection of such walls.

Figure 3 is a sectional elevational view of the construction shown in Figure 2, the section being taken on the line 3—3 of Figure 2, and

60

Figure 4 is a sectional plan view of a building construction illustrating several modified forms of a corner wall construction.

As pointed out above, my invention is particularly designed, although not limited to the uniting and connecting of walls composed of slabs or building units of cementitious material. Such units are preferably of the form disclosed in my pending application for Patent, Serial No. 170,773 filed Feb. 25, 1927, and 65 comprise spaced elements of cementitious material which are held in spaced relation by beams or webs preferably in the form of steel I-beams. These units are of sufficient thickness to form the wall of a building and vary in 70 width and height preferably having a rather large width and height so that only a very few of such units are required to form the wall of a building and indeed a wall may be formed of a single unit in some cases. Where the 75 building unit is used for the outside wall of the house or building the spaced elements of cementitious material which form the outside and inside surfaces are insulated from each other in any desired or preferred way so as to 80 prevent passage of cold or moisture through the unit into the interior of the house. Such insulation is not required where the building 85 units are used for the interior partition walls of the building or house.

90

In the accompanying drawings, I have illustrated my improved connecting means applied to various corner constructions. In the form of the invention shown in Figure 1, an outside corner of a building is shown. 95 One of the walls of this building includes an outer element 10 of cementitious material and an inner element 11 of like material, the two elements being spaced apart by webs or beams, one of which is shown at 12 as an end beam 100 preferably an I-beam. The outer surface of this I-beam preferably is provided with insulation 13 to keep out the cold as much as possible. This insulation is held in place as by means of prongs 14 or the like, struck up from the flange of the beam. The cementitious elements 10 and 11 are reenforced as by means of wire mesh 15 and 16 which may be joined or connected to the supporting elements or I-beams by prongs 17 or the like, 110 the latter being preferably struck out of the I-beams as disclosed in my pending applica-

110

tion Serial No. 174,496, filed March 11, 1927. The elements 10 and 11 are insulated from each other and to this end I preferably employ a plank 18 of insulating material which is supported in the grooves formed by channel irons 19 associated with the steel I-beams and preferably welded to the webs thereof.

The other wall is similarly formed. This wall in addition includes a portion 20 forming an elongated part of the element 10 of said wall and extending to the outer element 10 of the other wall. The end of the second wall is closed by the member 21 which forms a part of the outer element of said wall and a continuation of the outer element 10 of the first wall when the walls are assembled.

To the web of the end beam 12^a of the second wall, I preferably secure another beam 22 at right angles thereto as by means of rivets 23 or the like. The outer surface of the beam 22 serves as a support for the portion 21 of the outer element of the wall. In order to prevent the transmission of cold and moisture through the space between the beams 12^a and 22 I preferably provide an insulating member 24 which is supported in the grooves of channel irons 25 and 26 secured to said beams.

The beam 22, insulating member 24, as well as outer portions 20 and 21 are all associated as a unit and form a part of the second wall. This wall is connected to the first wall heretofore described by the novel connecting means of my invention. This connecting means is of such a character that it pulls and draws the walls together during application and holds and secures them firmly against one another so as to prevent any relative movement between the same, and locks and connects them together rigidly. This may be accomplished by a device which includes a bail, or eyelet member 27 associated with the web of one of the beams 12 or 22 and a hook member 28 clamped to the web of the other of said beams as by a nut 29. The hook member has a portion 30 which extends into the opening of the bail member when the walls are brought up together and so positioned with each other that the first wall is slightly elevated with respect to the second and the portion 30 is above the opening in the bail. The first wall is then released and allowed to fall. The portion 30 is forced into the opening in the bail as the first wall settles into position. The effect of this is to draw and pull the walls together and when the walls are in their final positions they are firmly and rigidly locked and connected together in such a way that no relative movement between them can occur. Another way in which this connection of the walls may be accomplished is by means of a channel element 31 which, when the walls are brought together is forced and clamped over the ends of the beams 12 and 22 and serves to pull and draw them together firmly and to hold

them rigidly and tightly against each other whereby the walls are securely and firmly tied together and relative movement between them is prevented. Other means for coacting with the beams 12 and 22 so as to pull and draw the walls together and rigidly hold them thus will perhaps occur to one skilled in this art and I do not confine myself to the details shown or to the specific manner in which the result is accomplished.

After the walls have been connected in the aforesaid manner, the space between the beams 12 and 22 is filled with grout 32 which also serves as a column when it sets and in order to prevent the transmission of cold and moisture through spaces, I preferably provide a member 33 of insulating material supported also in the grooves of channel members 34 and 35 associated with the beams 12 and 22. There may be a slight space or crack 36 left between the walls after they have been connected and such a space is also filled up with suitable grout or cementitious material.

In the application of the invention to the corner construction shown in Figures 2 and 3, the building units comprising the outer wall are securely and firmly united by means of a beam 40 which is fastened as by rivets 41 to the end beams 12^b of said walls but extends perpendicularly thereto as best shown in Figure 2. The partition wall of this application is connected to the outer wall by tying the end beam 12^c of said partition wall to the beam 40 which is common to the units comprising the outer wall. The connecting means in this case also may include a bail member 27^a associated with one of the beams 12^c or 40 and a hook member 28^a having a portion 30^a for entering the opening of the bail. In this case also when the walls are being joined and connected together the effect of the securing or connecting means is to pull and draw the walls together so as to tightly unite and join them. If desired a number of said hook and bail members may be used in the connecting of the walls and as shown in Figure 3 these members are preferably disposed in vertical alinement. In this form of the invention also I may use a channel element 31^a either at the top or bottom or at both the top and bottom. Such channel elements are forced over the tops or bottoms of the beams 12^c and 40 and serve to draw and pull them together when they are being applied so that when applied the walls are securely tied and rigidly connected together. If desired, these channel elements may be permanently secured as a part of the building and to this end they may be riveted or otherwise permanently secured in place.

After the walls have been connected in the above manner the space formed between the end beams of the various connected units is preferably filled with grout 42 and this

space also has an insulating member 43 carried in channel elements 44 associated with the end beams 12^b of the units comprising the outer wall. The space or crack 45 which 5 may be formed or left between the units comprising the outer wall is also preferably filled up with grout or any suitable or desirable cementitious material.

In Figure 4, I have disclosed the application of the invention in the connection of simple types of building units or slabs, which are designated by numerals 50, 51 and 52. By reference to said figure it will be noted that the slabs 50 and 51 are connected and 10 joined together by a channel element 30^b which coacts with the flange of the end beam 12^d of the unit 50 and the web of the end beam 12^e of the unit 51, being forced over either of the ends of said beams and serving 15 to draw and pull them together, thereby to tightly connect the units 50 and 51. Of course as in the former modifications and applications of the invention, the channel element or elements may be permanently 20 fastened in position after application, as by riveting to one of the beams, and it will be understood that such elements may be used both at the tops and bottoms of the beams. After the units have been connected in this 25 manner the space left between the beam 12^e and the unit 50 may be filled up with grout of any desired or preferred cementitious material 53. This grout as in the other modifications serves to impart greater stability and 30 strength to the resulting structure and also forms a solid vertical cementitious element which may act as a column for the resulting construction. The unit 52 is connected to the unit 51 also by a channel element or elements 35 which coacts with the web of the end beam 12^f of the unit 52 and also with the inner surface of the outer cementitious element forming part of the unit 51 and serves 40 to pull and draw the said units together while being applied and after application 45 serves to securely and tightly hold them together so as to prevent any relative movement therebetween. I have found it desirable in this construction to employ a metallic 50 reenforcing member 54 in the outer element of the unit 51 so that the channel element 30^c will not cause damage or fracture of said element during or after application. The channel elements in this application of the 55 invention may also be either detachably disposed in place or they may be permanently riveted if so desired. I also preferably employ grout 55 within the space formed by the beam 12^f and unit 51 which grout serves 60 to impart rigidity and greater strength to the construction obtained as well as to serve as a column for the resulting building.

By my invention I have thus provided 65 means for rigidly and securely connecting the units of a building construction together

whether the units are in the nature of walls of the building or slabs comprising said walls. This connecting means is of such character as to draw and pull the various units tightly and forcibly together during application and 70 to hold them rigidly and firmly in such tight cooperation whereby relative movement between them is prevented and a very strong, sturdy and stable structure is obtained in which there is no liability of cracking in the 75 cementitious material due to any relative movement between the various parts of the structure.

While I have described a number of specific 80 applications and modifications of the invention, it will be understood that the same is susceptible to many other modifications and applications and I desire to have this disclosure interpreted in as broad as possible a manner consistent with the state of the prior 85 art and the scope of the appended claims.

Having thus fully described my invention what I claim as new and desire to secure by Letters Patent is:

1. The combination with a plurality of 90 building units comprising spaced elements of cementitious material, and reenforcing members for spacing said elements, of means for connecting said units, said means comprising a rigid connection between reenforcing members 95 said connection acting during its application to draw the reenforcing members and to hold them tightly in assembled relation.

2. The combination with a plurality of 100 building units, each of said units comprising a pair of slabs in spaced parallel relation and a spacing element, of means for connecting said units, said means including a bail member associated with a spacing element in one 105 of said units and a hook member associated with a spacing element in another of said units for cooperation with said bail member.

3. The combination with a plurality of 110 building units of cementitious material placed in juxtaposition, each of said units comprising a pair of slabs in spaced parallel relation, of reenforcing elements in said units near the place of juxtaposition for spacing said slabs, and a rigid connection 115 between said elements serving to rigidly maintain the juxtaposed position of the units, said connection acting during its application to draw the reenforcing members and to hold them tightly in assembled relation.

4. A joint for concrete walls comprising in 120 combination a plurality of juxtaposed reinforced building units, one of said units consisting of a pair of concrete slabs and a metallic reinforcing element for spacing said slabs in parallel relation, means for rigidly connecting said spacing element to a reinforcing element of an adjacent unit, and a filler between said connected elements.

5. A joint for concrete walls comprising in 130 combination a plurality of juxtaposed re-

inforced building units, one of said units consisting of a pair of concrete slabs and a metallic reinforcing element for spacing said slabs in parallel relation, means secured to said spacing element for engaging a reinforcing element of an adjacent unit, and a filler of cementitious material between said connected units.

6. In combination, a plurality of juxtaposed reinforced building units, each of said units comprising spaced parallel slabs of cementitious material and reinforcing spac-

ing elements between the slabs, said units having end reinforcing elements near where they juxtapose, and means for rigidly connecting said end elements together, said means acting during its application to draw the end elements and to hold them tightly in assembled relation.

In testimony whereof, I have signed my name to this specification this 14th day of June, 1927.

OSCAR A. PEDERSEN.
